M. M. LEVINSON

ELECTRIC HEATING DEVICE

Original Filed April 12, 1921

INVENTOR:

MARCUS MICHAEL LEVINSON,

By: Otto H. Krueger,
his Atty.

UNITED STATES PATENT OFFICE.

MARCUS MICHAEL LEVINSON, OF PASADENA, CALIFORNIA.

ELECTRIC HEATING DEVICE.

Application filed April 12, 1921, Serial No. 460,640. Renewed September 10, 1923.

To all whom it may concern:

Be it known that I, MARCUS MICHAEL LEVINSON, a citizen of the United States, residing at Pasadena, in the county of Los Angeles and State of California, have invented a new and useful Electric Heating Device, of which the following is a specification.

This invention relates to devices for developing heat by electricity, inclosed in an insulated container.

One of the objects of this invention is to provide a tubular heater with a centrally insulated heating coil.

Another object is to provide a heating coil encased within insulating material within the housing of the device.

Another object is to provide a heating coil embedded in insulating material within the device to the extent to which the device is to be heated, having a coarser wire connecting to the coil and extending to the outside and also imbedded in insulating material in other parts of the device, not to be heated.

Other objects will appear from the following description and appended claims as well as from the accompanying drawing, in which—

30 Fig. 1 is a side elevation of a device embodying this invention.

Fig. 2 is a slightly modified form of a device also embodying the invention.

The devices illustrated in the drawing are provided with a metallic casing, especially suitable to radiate heat, and adapted to form a durable and compact whole, readily, conveniently, and safely to be handled.

40 The safety of such a device depends also on its insulation so that no short circuits may occur through its metallic casing.

A device of this type must furthermore be made so that only a limited and suitable portion of it becomes suitably heated while the remaining portion retains the possibly coolest outside.

The device illustrated in Fig. 1 is of a form to be used for heating water and other similar matter by disposing the device in such matter, only a proportionally small portion being liable to be heated while the rest retains a temperature easily handled.

50 This device is also used for use on automobiles, developing enough heat to vulcanize a tire and to be useful around an automobile

in many other ways, when attached to the battery of the automobile.

A wire coil 3, preferably made of nichrome, is embedded in insulating matter 4 within the tube 5. The insulating matter is preferably of magnesium oxide. The most convenient manner of embedding the coil within the tube concentrically so as to be insulated from the tube is by disposing the coil within the tube and also dispose the magnesium oxide in the tube before the tube is bent, allowing the magnesium oxide to set and harden with the coil in the center, after hardening, the tube being bent to suit.

In the device illustrated in Fig. 1, the tube 5 with the coil insulated in it is bent to bring the ends 6 and 7 into a position that the wires 8 and 9 can be connected to the ends 6 and 7. The outer terminations 10 and 11 of the wires 8 and 9 are provided to allow a connection of supplying current.

The wires 8 and 9 are of different type than the coil wire, besides being coarser and preferably practically straight, but also insulated, within the tubes 12 and 13. The tubes 12 and 13 are engaged with the ends of the tube 5, as indicated at 14 and 15. The opposite ends of the tubes 12 and 13 are embedded in the insulating socket 18, as indicated at 17 and 16. The wires 8 and 9 are preferably insulated by the same kind of material as used in the tube 5, as indicated at 4 in tube 13. The wires 8 and 9 and the coil 3 therefore entirely insulated from the tubes 5, 12 and 13, and, if the ends 10 and 11 are inserted into a common connecting socket, such insulation is complete and perfect, so that the operator cannot receive any shocks, and no short-circuit can be produced in normal use.

The circuit is complete, when connected to a source, from end 10, through wire 8, through coil 3, through wire 9 and back through end 11 to the source, the coil 3 being properly heated and producing a proper heating of the tube 5 between the points 14 and 15 since the coil is made of suitable material to assure such a heating or overheating to a suitable extent.

The device illustrated in Fig. 2 is a slightly modified form, but also designed to heat only a suitable portion of the outer tube. This device is illustrated as practically straight, but from the following description it will easily be understood that

the outer form does not materially influence the working and the principle of the device.

The coil 19 is embedded in the insulating material 20 within the tube-portion 21. The 5 termination of the tube is closed as indicated at 22. The material, designated 20, is preferably of the same type and origin as the material designated 4 in Fig. 1, to insure the same insulating effect as de- 10 scribed with reference to the device in Fig.

1. The whole tube from the end 22 to the end 23 is preferably of one piece, cut in at the points 24 and 25, leaving only small remaining connections as indicated at 26, 15 between the tube portions 21 and 27; but a similar and eventually the same effect may be obtained and procured by providing distinctly separate portions 21 and 27, connected by suitable proportionally small 20 pieces of metal or wires. This connection between the portion 21 and portion 27 of the tube is only provided for the purpose of keeping the portion 27 proportionally cool when the portion 21 is heated, such 25 small connections not transmitting too much heat while still forming good conductors between the tube portions 21 and 27, for electric purposes. The tube portion 27 reaches from the end 23 to the point 28, 30 near the cut outs 24 and 25. A coarser wire 29, less liable to be heated by the current passing through the device, is embedded in the same insulating material 20, within the tube portion 29, terminating outside of the 35 device, as indicated at 30. The one end of the coil 19 is connected to the tube end 22, as indicated at 31; or to the tube portion 21 near the end plate 22. The opposite end of the coil is connected to the one end of the wire 29, as indicated at 32.

The current supplying source is connected to this device at the end 30 of the wire 29 and to the end 23 of the tube.

The circuit is completed from the source, 45 through end 30, through the wire 29, through the coil 19, connecting at 31 with the tube, through the tube-portion 21, through the connections 26, and through the tube-portion 27 back to the source.

60 This device is especially suitable for a

soldering iron or bolt, since the front end 22 becomes suitably heated for soldering purposes.

The device may naturally also be used for many other purposes, the heating of a portion of the device to such an extent to make the device so useful being the principal point in view.

Having thus described my invention, I claim:

1. In an electric heater, an insulating socket, a casing, so that both ends terminate within the socket insulating material in the casing, a heating coil disposed and embedded centrally within the insulating material 65 within a portion of the casing, and a connecting wire disposed and embedded within the insulating material within the remaining portion of the casing and extending out of the casing before said insulating socket 70 to supply electric current to the insulated coil.

2. In an electric heater, a tube, insulating material in the tube, a heating coil disposed and embedded within the insulating material within a portion of the tube so as to heat that portion of the tube, and connecting wires disposed and embedded within the insulating material within the remaining portion of the tube and extending out of the tube to form the current-supplying means, the connecting wires being of suitable form so as not to heat the said remaining portion of the tube.

3. In an electric heater, a tube, insulating material in the tube, a heating coil embedded in the insulating material within a portion of the tube adapted to heat that portion of the tube, and a conductor connected to the coil being of material less liable to be heated than the coil and extending outwardly to form the current supplying means for the coil.

In testimony that I claim the foregoing as my invention I have signed my name in 95 the presence of two subscribing witnesses.

MARCUS MICHAEL LEVINSON.

Witnesses:

OTTO H. KRUEGER,
JESSIE A. MANOCK.
